LAMP HANGER WITH MULTIPLE CONTACTS

Thayer B. Farrington, Cleveland Heights, Ohio

Application May 1, 1940, Serial No. 332,634

8 Claims. (Cl. 173—324)

This invention relates to a lamp hanger for providing a plurality of separable electric connections, more than two, for supplying current to an electric fixture which is arranged to be latched in a raised position or lowered for purposes of repair, maintenance and the like.

The present invention provides a novel structure for providing a plurality of separable electric contacts, together with means for equalizing the contact pressure between the coacting pairs of contact members when the separable parts are engaged as occurs normally whenever the electrical fixture is in use. The novel features of the invention will be apparent from the accompanying drawings and specification and the essential features thereof will be set forth in the claims.

In the drawings, Fig. 1 is a central sectional view taken along the line 1—1 of Fig. 2 and showing one embodiment of my invention; Fig. 2 is an enlarged transverse sectional view taken along the line 2—2 of Fig. 1; Fig. 3 is an elevational view of one of the upper contact members taken at right angles to the view shown in Fig. 1; Fig. 4 is a bottom plan view of the structure of Fig. 3; Fig. 5 is an end elevational view of one of the bottom contact members and support therefor of Fig. 1; Fig. 6 is a top plan view of the structure of Fig. 5; Fig. 7 is a bottom plan view of the structure of Fig. 5 taken from approximately the position indicated at 7—7 on Fig. 5; Fig. 8 is a sectional view taken along the line 8—8 of Fig. 5; Fig. 9 is a sectional view taken along the line 9—9 of Fig. 6; Fig. 10 is a view similar to Fig. 8 showing a modification in which the equalizer bar is in a different position; Fig. 11 is a view similar to Fig. 9 showing a modification as to another detail; Fig. 12 is a view similar to Fig. 2 showing an arrangement providing three pairs of contacts; while Fig. 13 is a view showing still another modification providing for six pairs of contacts.

My invention relates to improvements in lamp hanger structures adapted for supporting lamps in elevated position and for lowering the same for repairs and maintenance. The present invention is directed to the provision of a plurality of electrical contacts in such lamp supporting structures. One place where such an invention is useful is where standard incandescent lamps and mercury lamps are supported in the same fixture. In such a case different voltage is necessary for the two lamps and a plurality of contacts is necessary. Four contacts may be used, two for each voltage or sometimes three contacts

may be used if an auto-transformer is provided. Other uses for my improved multiple contact devices will readily occur to those skilled in this art.

5 The structure shown in the present embodiment comprises a main lamp hanger member 10 generally mounted in a fixed position at some elevated point in a building or on a structure of any sort, preferably by means of a combined bracket and sheave housing 11 through which the chain or cable for manipulation of the lowering hanger member is conducted away to some remote point. The main hanger member comprises a tubular guide 13 rigidly secured to the main hanger member and having a hollow central portion for receiving and embracing the guide stem 14 of the lowering hanger member 15. The stem 14 has a fin 14a which enters a slot 13a in the tubular guide, being guided to that position by the cam surface 16. The latch 17 holds the stem 14 in position latched to the guide 13 as is more fully described in my co-pending application Serial No. 298,982, filed October 11, 1939. The main hanger member has secured to it two blocks 18 of insulating material. One of these blocks is shown in elevation in Fig. 3 and in bottom plan view in Fig. 4. Suitably mounted in these blocks is a pair of contacts 19 which may be secured to the block 18 as by means of the bolts 20a. It will be noted that the contacts 19 are of cup-shape form opening downwardly to coact with the movable contacts. Preferably a flange or shoulder 18a of insulating material extends downwardly between the two contacts 19 on each of the blocks 18 so as to electrically shield the contacts from each other. A recess 20 extends laterally away from each contact 19 to permit the attachment of wires 21 to the contacts 19. It will be understood that these wires 21 enter the enclosing canopy 22 either through the top or side wall thereof and are connected to the electrical system.

45 The lowering hanger member 15 comprises a spring housing 23 surrounding the stem 14, the two parts being yieldably connected by means of a spring 24 which is compressed between a flange 14b on the stem 14 and a flange 15a on the housing 23. It will be noted in Fig. 1 that the stem 14 is hollow so as to accommodate the lowering chain or cable 25 which is suitably secured within the stem 14 and normally passes out through the sheave housing 11 and downwardly to a point within easy reach of an operator. The resilient connection provided by the

spring 24 permits a raising of stem 14 and the hanger member 15 above the position of Fig. 1 in order to disengage the latch 17 so as to permit lowering of the movable hanger member. The spring 24 also permits sufficient tilting movement between stem 14 and housing 23 to equalize pressure between the contacts carried by the left- and right-hand arms 15b of Fig. 1. Formed as a portion of the member 15 are the laterally extending brackets 15b which support the lower or movable electrical contact members.

These lower contact members are preferably supported in pairs in a manner to permit relative vertical movement between the two members 26 of a pair so that they may fully engage the coacting pair of contacts 19. To this end each contact 26 may be mounted in a separate insulating block as shown in Figs. 5 to 9 or the contacts may be in one block as shown in Fig. 11 with a flexible portion between the contacts. Referring particularly to Figs. 5 to 9, one of the lower contact members is shown at 26 secured to a block of insulating material 27 by means of a screw 28. A strip of electrical conducting material 29 molded in the block 27 passes from a point above the bracket 15b to a point therebeneath where it is provided with a binding post 30. Referring to Fig. 6, it will be noted that the top of the block 27 is provided with a recess 27a opening outwardly to one side providing a pocket sufficient to accommodate the coacting contact 19. It will be noted that this recess leaves a wall 27b on each block 27 which serves to shield the contacts 26 from each other. Referring to Figs. 5 and 6 it will be noted that a pair of blocks 27 coact to provide a recess 31 for the accommodation of the projection 18a of the upper contact carrying block 18. Thus when a pair of contacts 19 and 26 are in engagement each pair of contacts is housed on three sides by the insulating material so that they are electrically completely separated from each other. Referring especially to Figs. 1, 5 and 7, it will be noted that the blocks 27 at their lower ends are provided with recesses 27c permitting the easy introduction of wires 32 to the binding posts 30. Here again the material of the blocks 27 surrounds the binding posts 30 on three sides so that they are electrically separated from each other. It will be understood by those skilled in this art that the wires 32 lead inwardly through openings 33 in an adapter 34 and thence extend downwardly to electrical fixtures.

It will be noted that each block 27 has a centrally located narrow portion 27d intermediate its ends at the point where the block passes through the bracket 15b. This bracket has a semicircular recess opening outwardly and the portions 27d of a pair of blocks 27 together form a substantially cylindrical shaft which is fairly snugly embraced by the semicircular recess 35 in the bracket 15b. Means is provided for holding the blocks 27 in the recess 35. The means here provided comprises a keeper bar 36 having bifurcated ends 36a which embrace the bracket portion 15b to which they are secured as by means of cotter pins 37. The blocks 27 are prevented from turning when locked in position by the keeper bar 36 by reason of the arcuate side face portions 38 which as shown in Fig. 7 closely approach the housing 23. By making similar arcuate faces at 38a the blocks 27 are identical.

As mentioned above, the spring 24 and the arrangement of the parts permits a relative tilting movement of the lowering hanger member with

respect to the main hanger member so that the pair of contacts seen at the left in Fig. 1 and the pair of contacts seen at the right in the same view have their contact pressure equalized when the hanger members approach each other and are latched together. This tilting occurs in a plane generally parallel to the sheet as viewed in Fig. 1. I also provide novel means for permitting equalization of contact pressure between each two pairs of coacting contact members either at the right or the left as seen in Fig. 1. To this end a single pair of contact members 26 as assembled in a single unit as viewed in Fig. 5 is permitted to oscillate in a plane at right angles to the sheet as viewed in Fig. 1. In other words the equalization of the pressure between a group of two contact members 26 on one side of the coacting guiding parts 13, 14 is in a plane generally at right angles to a plane generally represented by the line 1—1 of Fig. 2. A special form of equalizer bar 39 is provided for this purpose. This bar is generally of H-like form as best seen in Figs. 8 and 9 and comprises a central cross bar 39a, which is embraced between a pair of blocks 27, and end bars 39b which underlie the upper portions of the blocks 27. To this end the upper surface of each bar 39 is generally plane and the blocks 27 have plane surfaces 27e where they rest upon the upper face of the bar 39. As best seen in Fig. 9, the blocks 27 are recessed at 40 so as to embrace the cross bar 39a. Thus when a pair of blocks 27 are assembled in the bracket 15b and held by a keeper bar 36, the equalizer bar 39 is held in position. To permit a tilting action of the equalizer bar 39, it is provided with a downwardly extending knife edge 41 running longitudinally of the cross bar 39a and resting as shown in Fig. 1 at one end upon the keeper bar 36 and at the other end upon the bracket portion 15b. These coacting portions which engage the knife edge 41 are arranged at the same level for this purpose. Obviously when the pair of lower contacts 26, as viewed in Fig. 5, approach a pair of upper contacts 19, as shown in Fig. 3, the bar 39 permits oscillation of the movable contact members so as to equalize contact pressure between the two pairs of coacting contact members. Clearance between the parts at this time permits alinement of coacting contacts. All of the contact members on the coacting hanger members are resiliently held in engagement by the spring 24 when the parts are in latched position as viewed in Fig. 1.

The bar 39' of Fig. 11 may be a straight bar with little or no end pieces as would be necessary with such a construction. One or more pins 42 may be provided to prevent the bar moving endwise. It will be understood that bridge 43 is flexible enough to permit relative vertical movement between the two contacts 26.

In Fig. 10 I have shown a modification which will be readily understood upon reference to Fig. 8. It will be recalled that in the form shown in Fig. 8 the tilting or oscillation of the two contacts 26 forming a single group occurred in a plane at right angles to the tilting of the parts 14 and 23 relative to each other. In the modification of Fig. 10 the structure is in all respects similar except that the H-like bar 39 has been turned 90° from the position shown in Fig. 8. Here as before the construction permits a tilting of the blocks 27 and their associated contacts 26 but the tilting occurs in approximately the same plane as the tilting between the parts 14 and 23.

If necessary, the blocks 18 carrying the contacts 19 could be turned 90° from the position of Fig. 1.

If necessary or desirable the device would obviously work equally well if, for instance, two pairs of coacting contact members as have just been described were provided on the left-hand side of Fig. 1 while a single pair of coacting contact members 19, 26 were provided at the right-hand side thereof. This arrangement is shown in Fig. 12. The single contact shown at the right is similar to that shown in my above-named copending application. In such a case the relative tilting between the parts 23 and 14 would permit equalization between the left- and right-hand sides while the equalizer bar 39 on the left-hand side would permit equalization between the two contacts located there.

In Fig. 13 I have shown a modification which provides for six pairs of contacts. In this form the hanger member 15 is provided with three bracket portions 15b extending outwardly from the main housing 23. Each of these bracket portions supports a pair of contacts 26 in the manner described in connection with the first form hereinabove mentioned. All of the other parts are exactly as described in connection with the first form, it being understood of course that six fixed contacts 19 are provided on the hanger member 10 instead of the four contacts disclosed in connection with the first form. As the lowering hanger member approaches the main hanger member there will first be a three-point equalization between the parts carried by the three bracket portions 15b. The final equalization will occur between each pair of contacts supported by one of the equalizer bars 39. The canopy should house all of the contacts and is here shown circular.

If the teaching of Fig. 12 is applied to Fig. 13 any number of pairs of contacts between 3 and 6 may be provided.

What I claim is:

1. Electrical contact supporting means comprising a bracket providing a recess open at one side, a keeper bar for closing the open side of said recess, a pair of insulator blocks adapted to be embraced and held by said bracket recess and said keeper bar, electrical contacts mounted one on each block, rigid bar means held between said blocks and supporting each block, said bar means having a downwardly extending knife edge extending normal to a plane passing through said contacts, and said knife edge having one end resting upon said keeper bar and having its other end resting upon said bracket.

2. The combination of claim 1 wherein said bar means is of H-like form, and said knife edge extends along the central cross-bar thereof.

3. In a lamp hanger structure having coacting separable and lowering hanger members having interfitting centrally located guiding parts adapted to coact when said members engage, the combination of three arms on said lowering hanger member spaced circumferentially about said guiding parts, a pair of contact members on each of said arms, coacting pairs of contact members on said main hanger member, and equalizer bar

means for equalizing the engaging pressure of the pair of contact members on each arm.

4. Electrical contact supporting means comprising a bracket providing a recessed opening, 5 a pair of insulator blocks in said recess, an electrical contact on each block, a keeper bar connected with said bracket and engaging said blocks and holding said blocks in said recess, and equalizer bar means providing a pivotal support for said blocks located between said blocks and permitting oscillation of said blocks about said pivotal support, whereby to equalize pressure on said contacts when they are moved to a position engaging other contacts.

5. Electric contact supporting means comprising pivot means, a pair of insulator blocks on opposite sides of said pivot means and supported thereby, an electrical contact on each block, and flexible means connecting said blocks and permitting relative vertical movement between them, 20 whereby to equalize pressure on said contacts when they are moved to a position engaging other contacts.

6. In lamp hanger structure comprising a 25 bracket having a plurality of recessed openings each adapted to receive a contact-carrying unit, and having a keeper bar connected with said bracket at each recess, each bar engaging its associated unit and holding said unit in its recess, the combination of a two-block contact 30 unit having two insulator blocks adapted as a unit to be held in one of said recesses by one of said bars, an electrical contact on each of said last named blocks, and equalizing means carried by said unit for providing relative vertical movement between said contacts on said two-block unit.

7. Electrical contact supporting means comprising a bracket having a recessed opening, a pair of insulator blocks adapted when placed adjacent each other as a pair to fit in said recess, an electrical contact on each block, a keeper bar connected with said bracket and engaging said blocks and firmly holding them in said recess, 45 equalizer bar means providing a pivotal support for said blocks located between said blocks and permitting oscillation of said blocks about said pivotal support, whereby to equalize pressure on said contacts when they are moved to a position 50 engaging other contacts, and there being recesses in adjacent faces of said insulator blocks which, when said blocks are placed together in a pair, embrace and hold said equalizer bar means.

55 8. Electrical contact supporting means comprising bracket means providing an opening, a pair of insulator blocks in said opening, said bracket means cooperating with said blocks to hold the latter in said opening, an electrical 60 contact on each block, and equalizer bar means providing a pivotal support for said blocks located in a plane between said blocks and permitting oscillation of said blocks about said pivotal support, whereby to equalize pressure on 65 said contacts when they are moved to a position engaging other contacts.

THAYER B. FARRINGTON.
